PROCESS OF REFINING HYDROCARBON OILS

David F. Gould, Riverton, N. J., assignor to The Barrett Company, New York, N. Y., a corporation of New Jersey

No Drawing. Application August 2, 1937,
Serial No. 156,947

3 Claims. (Cl. 196—35)

This invention relates to the refining of crude hydrocarbon oils and particularly to the refining of oils obtained in the gasification or carbonization of coal or production of carburetted water gas, such as, for example, coke oven light oils, drip oils, coal tar and water gas tar distillates, etc., which are hereinafter referred to as aromatic hydrocarbon oils.

It is well known to refine hydrocarbon oils by treating them with concentrated sulfuric acid (66° Bé.) to remove tarry and gum-forming constituents. This method is not only wasteful, due to a substantial loss of oil which is sulfonated by the acid, but the concentrated acid causes by-products to be formed, which remain in the oil and, on storage, produce color changes in the oil. It has been proposed to treat hydrocarbon oils with sulfuric acid of a strength below 66° Bé. According to this proposal, the oil is treated with sulfuric acid which may be of a strength below 60° Bé., after which the acid is drawn off, the oil neutralized with caustic soda, and the purified oil removed by steam distillation.

I have made the surprising discovery that by treating the crude hydrocarbon oil with sulfuric acid of a strength below that at which sulfonation of the oil readily takes place and then distilling the oil from the mixture without first removing the acid, refined oil is obtained which is superior with respect to its color stability on storage to oils heretofore produced by the acid refining of crude hydrocarbon oils.

According to my invention, hydrocarbon oils, such as benzol, toluol, xylol, or mixtures of such oils, solvent naphtha, drip oils, etc., are treated with a sulfuric acid solution containing less than 70% H₂SO₄ and thereafter, without removing the sulfuric acid, the mixture is distilled to drive off the refined oil therefrom. The oil-acid mixture is heated to facilitate the reaction of the acid upon the unsaturated compounds in the oil. This heating may be accomplished in bringing the mixture up to the distillation temperature; or if desired the mixture may be slowly heated to a point below the distillation temperature and maintained at such temperature until the action of the acid on the unsaturated compounds is completed; but preferably the heating is accomplished by refluxing the mixture until the action of the acid on the unsaturated compounds is completed so that substantially complete separation of the reaction products of such unsaturates may then be effected. After the refined oil is distilled from the mixture, it is neutralized to

remove the small amount of acidic impurities which come over with the oil during the distillation. The polymerizable constituents of the crude oil are polymerized by the sulfuric acid and the products remain in the vessel as a liquid or low melting polymer, and may be recovered in any suitable manner.

According to the preferred embodiment of my invention, the crude hydrocarbon oil is refluxed with a sulfuric acid solution containing between about 50% and about 70% H₂SO₄, preferably between about 60% and about 65% H₂SO₄. The amount of acid used and the time of refluxing are to some extent dependent on one another, for if a relatively large amount of acid; e. g., 20% by volume of the oil, is used, the time may be relatively short; e. g., ½ hour, while a relatively small amount of acid; e. g., 7% by volume of oil, may require a relatively long refluxing time; e. g., 4 or more hours. The use of the larger amount of acid is preferred and the excess is recoverable for reuse since it is not wasted in sulfonation of the oil as is the case when 66° Bé. acid is used. The temperature at which the mixture is refluxed is regulated according to the boiling point of the lowest boiling constituent of the mixture. Thus, for crude solvent naphtha or other relatively low boiling oils, the temperature is determined by the boiling point of the oil e. g., 110° C. for crude drip oil solvent naphtha, while in the case of the higher boiling oils, such as hiflash naphtha, the refluxing temperature is limited by the boiling point of the acid used; e. g., 123° C. for 50% acid and 165° C. for 70% acid. After the acid treatment is finished, in the case of higher boiling oils the mixture is held at a temperature just below the boiling point of the acid used and is steam distilled at this temperature to remove the volatile oil from the mixture without carrying over substantial amounts of acid.

The following example is illustrative of this invention:

Example 1.—5 parts by volume of crude hiflash naphtha obtained from drip oil (the oil condensed in mains through which coal distillation gas or carburetted water gas is passed) having a boiling range between about 150° and about 200° C. were refluxed for ½ hour with 1 part by volume of 65% sulfuric acid. Without removing the acid, the mixture was steam distilled at a still temperature of 135° to 140° C., the resultant distillate was neutralized with caustic soda solution and then fractionated into solvent naphtha and hiflash naphtha fractions. These frac-

tions showed satisfactory color stability on storage for nine months, and had acid wash tests (hereinafter described) of 10 and 6, respectively.

While the above example describes a batch operation, the invention can be carried out continuously by treating the oil with acid in a countercurrent scrubber and continuously distilling purified oil from the mixture after a suitable time of contact.

10 The wash test hereinabove mentioned is described by Weiss, "Industrial and Engineering Chemistry", Vol. 10, page 1008 (1918). In this method of grading refined oils, the oil is washed with acid and the color of the acid layer after 15 the washing is compared with standard colors designated by numbers from 0 to 14, or in a second series by numbers from C-1 to C-10. The color No. 14 in the former series corresponds to C-7 in the second series. Thus the color of the acid used in testing the oil is said to vary progressively from No. 0 to No. 14, C-8, C-9, and C-10, in varying from water-white through yellow to brown.

15 The following example illustrates the superiority of the process of this invention over previous processes for refining crude hydrocarbon oils with respect to removal of substances darkened by concentrated sulfuric acid:

20 *Example 2.*—5 parts by volume of crude solvent naphtha having a boiling range between about 112° and about 187° C. were refluxed for 1/2 hour with 1 part by volume of 65% sulfuric acid. The refined oil was then distilled from the mixture without removing excess acid and the distillate 25 neutralized and fractionated into solvent naphtha and hiflash naphtha fractions. These fractions showed acid wash tests of 8+ and 7, respectively. The same crude oil was then refluxed with the same proportion of acid as above for 2 hours, but 30 excess acid was removed and the oil neutralized before distillation. The solvent naphtha and hiflash naphtha fractions obtained on fractionation of the distillate showed acid wash tests of 10 and 14+, respectively.

35 A further example illustrates the superiority of the process of this invention over previous processes for refining crude hydrocarbon oils with respect to color stability of the refined oil on storage:

40 *Example 3.*—The same crude solvent naphtha as used in Example 2 was refluxed for 1/2 hour with the same proportion of 65% sulfuric acid, the refined oil distilled from the mixture without removing excess acid and the distillate neutralized; on fractionation the distillate gave fractions 45 within the range of column temperatures of 125° to 185° C. These fractions showed good color stability on storage for nine months exposed to diffused light. On the other hand, when the same crude oil was refined by the usual method, wherein it was treated with concentrated sulfuric acid (about 93%), the acid sludge removed and the oil neutralized, washed with water and fractionally distilled, the distillates obtained averaged 3% less 50 in volume than those obtained by the process of this invention, and on storage for one month, un-

5 der the same conditions as above, darkened in color and showed a precipitation of material of a soft resinous character.

6 The above tests show the superiority of the oil refining process of this invention. One possible explanation for the improved results obtained is that during the distillation of acid-treated oils resulting from the ordinary method of refining, some of the constituents of the oil decompose, producing distillable unsaturates which tend to 10 discolor the oil distillate on storage; where, however, the oil is distilled, as in accordance with this invention, in the presence of the acid, such unsaturates are acted on by the acid and converted to forms which do not distill over, a distillate product of improved wash test and color stability being thus obtained.

15 From the above it will be noted that by this invention refined hydrocarbon oils may be produced which show either a lower acid wash test 20 or improved color stability, or both, as compared with oils refined by prior methods. Moreover, this invention results in a saving of oil because substantially less sulfonation occurs than is the case when acid of 66° Bé. strength is used. Furthermore, this invention permits the refining of 25 the oil with the consumption of less acid and substantially reduces the time necessary as compared to prior methods.

30 Since certain changes may be made in carrying out the above process without departing from the scope of the invention, it is intended that all matter contained in the above description shall be interpreted as illustrative and not in a limiting sense.

35 I claim:

1. A process of refining a hydrocarbon oil from the group consisting of benzol, toluol, xylol, or mixtures thereof, solvent naphtha and drip oil which comprises adding sulfuric acid of a 40 strength not exceeding about 70% H_2SO_4 to said oil, heating the resulting mixture in the liquid phase, thereafter, without neutralizing acidic constituents in the oil, distilling off the oil, and then neutralizing acidic constituents in the resultant oil distillate.

2. A process of refining an aromatic hydrocarbon oil which comprises adding sulfuric acid of a strength not exceeding about 70% H_2SO_4 to said oil, heating the resulting mixture in the liquid phase and, without neutralizing acidic constituents in the oil, distilling off the oil and then neutralizing acidic constituents in the resultant oil 50 distillate.

3. A process of refining a hydrocarbon oil from the group consisting of benzol, toluol, xylol, or mixtures thereof, solvent naphtha and drip oil which comprises adding sulfuric acid containing between about 50% and about 70% H_2SO_4 to said oil, heating the resulting mixture in the liquid phase, thereafter, without neutralizing acidic constituents in the oil, distilling off the oil and then neutralizing acidic constituents in the resultant oil 60 distillate.
